UNITED STATES PATENT OFFICE.

MILTON C. WHITAKER AND WALTER F. RITTMAN, OF NEW YORK, N. Y., ASSIGNORS TO
SYNTHETIC HYDRO-CARBON COMPANY, OF PITTSBURGH, PENNSYLVANIA, A COR-
PORATION OF DELAWARE.

MANUFACTURE OF GAS.

1,327,001.

Specification of Letters Patent.

Patented Jan. 6, 1920.

Application filed April 3, 1914. Serial No. 829,169.

To all whom it may concern:

Be it known that we, MILTON C. WHITAKER and WALTER F. RITTMAN, both citizens of the United States, residing in the borough of Manhattan, city, county, and State of New York, respectively, have invented certain new and useful Improvements in the Manufacture of Gas; and we do hereby declare the following to be a full, clear, and 10 exact description of the invention, such as will enable others skilled in the art to which it appertains to make and use the same.

Our invention has for its purpose, primarily increasing the yield of gaseous illuminants obtained as a result of the cracking of hydrocarbon oils, and likewise involves increasing the total yield of fixed gases from such oils, so that the resulting gaseous product has not only a higher illuminating value, 20 but a higher heating value as well.

The invention is based upon the discovery that by the cracking up of the oil into gases at reduced pressures, as hereinafter specified, the proportion of "illuminants," that 25 is to say, the unsaturated series of hydrocarbons, such as ethylene, acetylene, etc., is increased to an extent which assumes commercial proportions when the pressure prevailing in the generating chamber or chambers 30 is reduced to two-thirds of an atmosphere absolute and which, at still lower pressures is further rapidly augmented, reaching a maximum within the range of from 4 lbs. pressure absolute downward. The increased 35 yield in the unsaturated series of gaseous hydrocarbons, by the practice of the invention, is also accompanied, although to a lesser degree, by an increase in the saturated series, such as methane, which accordingly 40 add to the heating value of the final product. The invention is particularly applicable to oils of the petroleum type such as crude petroleum, shale oil, etc.

The process is applicable not only to the 45 production of oil gas *per se*, but also for bringing water gas up to the commercial standard of candle power by combining the fixed gases due to the cracking up of the oil with the original uncarbureted water gas. 50 In fact, inasmuch as the required candle power for carbureted water gas is directly dependent upon the percentage of illuminating constituents contained in the gases resulting from the cracking up of the oil, the

amount of unsaturated hydrocarbons or illuminants obtained from a given quantity of oil, becomes a matter of special importance in the manufacture of carbureted water gas. 55

For purposes of illustration, we have shown in the accompanying drawing, in part 60 diagrammatically, an exemplification of a simple form of apparatus adapted to the practice of this invention, although it will be understood that the particular apparatus shown is but typical of many others having 65 the same capabilities.

Referring to the drawing, A indicates a refractory tube, which, in this instance, constitutes the gas generator, and which is capable of withstanding the vacuum incident 70 to the practice of the invention. In order to controllably heat the retort any suitable means may be employed as, for example, a resistance-wire wrapping *a*, enveloping the gas generating tube A and suitably insulated therefrom. The gas generator A and its electric heating element are incased in a protective coating of magnesia, asbestos, or other like refractory material, adapted to prevent excessive radiation of heat into the 75 surrounding atmosphere. One end of the resistance coil is connected to a binding post *b* and the other end through a conducting rod *c* to the binding post *d*. From these binding posts suitable conductors lead to an 80 appropriate source of electric energy, as, for instance, a direct current generator. A rheostat B is provided for controlling and regulating the current supply to the coil in accordance with the heat effects desired. 90

Midway of the tube A is located the branch *e*; through which is inserted a suitable pyrometer couple whereby the temperature prevailing within the generator may be read from an appropriate instrument. 95 A supporting rod *f* provided at its top with a disk *f'* having a series of perforations serves to support a small quantity of refractory filling material *g* (as, for instance, steel balls) located in the upper portion of 100 the generating tube A and within the same, the functions of this filling material being to afford an efficient spreading surface for the vaporization of the petroleum oil used. The oil is supplied to the top of the generator A above the filling material *g*, from a suitable source of supply, as, for instance, the feeding cup or receptacle C. The pres-

sure in the upper part of the feed cup or receptacle is equalized with that in the tube A through an equalizing pipe *t* communicating at its lower end with the tube A, and at 5 the other end above the level of the oil in the feed cup C. The generating tube A may also be provided with a suitable gage *s* to indicate the pressure prevailing therein.

At the lower end, the generating tube A 10 discharges through a condenser D into a receptacle E for the collection of liquid condensates. The gaseous products evolved during the operation are continuously withdrawn through the pipe *n* by means of a 15 vacuum pump G, which, in turn, discharges them into a gas holder H, as shown, or, if necessary, through a scrubber or purifier before reaching the gas holder.

The operation of the invention in the 20 form of the apparatus shown is as follows: The generating tube A is first heated to the desired temperature for cracking the oil into fixed gases, by passing an electric current of appropriate wattage through the 25 heating element *a*. When the generating tube A and the filling material *g* contained therein have attained the appropriate temperature, the oil feed is opened and the oil is permitted to enter the upper part of the 30 generating tube A where it spreads over the filling material and is vaporized. In the meantime, the vacuum pump G has been set in operation and draws the oil vapors downward into the cracking zone of the 35 generating tube A, whereupon these vapors are immediately cracked up into fixed gases and other products. These products, before opportunity is offered for polymerization or decomposition of the hydrocarbon gases, 40 are withdrawn by the vacuum pump G from the cracking zone and their place is taken by a quantity of oil vapor from the zone of filling material *g* above. In this manner and continuously the hydrocarbon gases, as 45 quickly as they form, are withdrawn and after passing through the condenser and receiver for the removal of the condensable vapors, solids, etc., are forwarded through the vacuum pump G to the gas holder.

50 As hereinbefore indicated, it is preferred to reduce the pressure as close to zero as is appropriate to the cracking of the oil vapors under the conditions of the operation. The degree of this temperature will, 55 it is evident, depend in part upon the length of time the vapors remain in the cracking zone. In other words, if the cracking zone is of extremely high temperature, the speed of travel of the gases should be correspondingly expedited. For general purposes, 60 however, and with apparatus of the kind and relative dimensions indicated in the drawing, a temperature of approximately 900° C., as indicated by the pyrometer, is 65 appropriate and sufficient; it being under-

stood, as indicated, that should the cracking zone be of greater heat intensity, it should be of lesser extent, so that the gaseous hydrocarbons formed may not suffer decomposition or polymerization by remaining too 70 long in contact with the hot surfaces which produce them.

The pressure prevailing within the system is indicated by the pressure gage *s* referred to, or may be further verified by the 75 mercury column *m* communicating with the gas exit pipe *n* leading into the vacuum pump.

We have found that increased yield in gaseous hydrocarbons, particularly in gaseous illuminants of the unsaturated hydrocarbon series begins to assume commercial importance at a reduced pressure equivalent to two-thirds of an atmosphere absolute. From this point, which may be regarded as 80 the "critical point" in the process, the increase in yield assumes rapidly increasing importance from this critical point, if the pressure is further reduced, and, in the range beginning with about 4 lbs. pressure 85 absolute approximates a yield which attains an increase of 100% in illuminants over the yield at atmospheric pressure.

We have further ascertained that the 90 operation of the invention is not interfered with by passing through the generator tube, during the operation, hydrogen, or hydrocarbon gases such as methane; nor is it interfered with by the presence of carbon monoxide (as, for instance, in the proportion in 95 which carbon monoxide exists in uncarnbureted water gas) unless the conditions of temperature and of relative concentration are such as to result in an unfavorable 100 "equilibrium" in the sense in which that 105 term is used in physical chemistry.

What we claim is:

1. The method of increasing the yield of an unsaturated hydrocarbon series from a hydrocarbon oil of the petroleum type, which 110 comprises cracking the hydrocarbon when in a gaseous state under appropriate conditions of temperature, at a pressure lower than two-thirds of an atmosphere absolute, substantially as described.

2. The method of increasing the yield of an unsaturated hydrocarbon series from a hydrocarbon oil of the petroleum type, which 115 comprises cracking the hydrocarbon when in a gaseous state under appropriate conditions of temperature, at a pressure lower than four pounds to the square inch absolute, substantially as described.

3. The method of increasing the yield of gaseous hydrocarbons, particularly gaseous 120 illuminants of the unsaturated hydrocarbon series, from a hydrocarbon oil of the petroleum type, which comprises vaporizing the oil, cracking the oil vapors into fixed gases, 125 continuously supplying the oil vapors to the 130

cracking zone, and continuously withdrawing the products developed as a result of the cracking, at a pressure less than two-thirds of an atmosphere absolute; substantially as 5 described.

4. The method of increasing the yield of gaseous hydrocarbons, particularly gaseous illuminants of the unsaturated hydrocarbon series, from a hydrocarbon oil of the petroleum type, which comprises vaporizing the oil, cracking the oil vapors into fixed gases, continuously supplying the oil vapors to the cracking zone, and continuously withdrawing the products developed as a result of the 10 cracking, at a pressure less than 4 lbs. to the square inch absolute; substantially as described.

5. The method of cracking hydrocarbon oils of the petroleum type, which consists in vaporizing the oil, and thereafter heating the vapors to a cracking temperature while under a pressure lower than two-thirds of an atmosphere absolute.

6. The method of cracking hydrocarbon oils of the petroleum type, which consists in vaporizing the oil in the upper portion of an upright reaction chamber, thereafter subjecting such vapors in a downwardly moving column to a cracking temperature while under a pressure substantially below atmospheric pressure and of the order described, and withdrawing the products of cracking from the bottom of such column.

7. The method of cracking hydrocarbon oils of the petroleum type, which consists in

vaporizing the oil in the upper portion of an upright reaction chamber, thereafter subjecting such vapors in a downwardly moving column to a cracking temperature while under a pressure lower than two-thirds of an 40 atmosphere absolute and withdrawing the products of cracking from the bottom of such column.

8. The method of cracking hydrocarbon oils, which comprises passing the same into 45 the upper portion of an upright heated unobstructed reaction chamber maintained at a cracking temperature, maintaining within said chamber a pressure substantially below atmospheric pressure and of the order described 50 and withdrawing the products of cracking from the bottom of such chamber.

9. The method of cracking hydrocarbon oils of the petroleum type which consists in vaporizing the oil in the upper portion of 55 an upright reaction chamber, thereafter subjecting such vapors in a downwardly moving column to a cracking temperature while under a pressure substantially below atmospheric pressure, withdrawing the products 60 of cracking from the bottom of such column, passing such products through a condenser and collecting the permanent gases.

In testimony whereof we affix our signatures, in presence of two witnesses.
